(57) **CLAIM**

The ornamental design for a coupling element adaptor for a pelt board, as shown.

DESCRIPTION

FIG. 1 is a front, bottom, and left side perspective view of a first embodiment of a coupling element adaptor for a pelt board in accordance with our design;

FIG. 2 is a top, front, and left side perspective view of a first embodiment of the coupling element adaptor for a pelt board shown in FIG. 1;

FIG. 3 is a top plan view of a first embodiment of the coupling element adaptor for a pelt board shown in FIG. 1;

FIG. 4 is a bottom plan view of a first embodiment of the coupling element adaptor for a pelt board shown in FIG. 1;

FIG. 5 is a front, bottom, and left side perspective view of a second embodiment of a coupling element adaptor for a pelt board in accordance with our design;

FIG. 6 is a top, front, and left side perspective view of a second embodiment of the coupling element adaptor for a pelt board shown in FIG. 5;

FIG. 7 is a top plan view of a second embodiment of the coupling element adaptor for a pelt board shown in FIG. 5; and,

FIG. 8 is a bottom plan view of a second embodiment of the coupling element adaptor for a pelt board shown in FIG. 5. The broken lines in the drawings illustrate portions of the coupling element adaptor for a pelt board that form no part of the claimed design.
